Primary Examiner — Abraham Bahta(74) Attorney, Agent, or Firm — Harrity & Harrity, LLP(57) CLAIM

The ornamental design for a transaction card, as shown and described.

DESCRIPTION

FIG. 1 is a front perspective view of the transaction card showing our new design;

FIG. 2 is a rear perspective view thereof.

FIG. 3 is a left side view thereof.

FIG. 4 is a right side view thereof.

FIG. 5 is a top view thereof; and,

FIG. 6 is a bottom view thereof.

The broken lines shown in the figures illustrate the environment and form no part of the claimed design.
